UNITED STATES PATENT OFFICE.

HARRY L. MERRIMAN AND TONY MAY, OF WOODLAWN, PENNSYLVANIA.

RAIL-JOINT.

1,142,266.

Specification of Letters Patent. Patented June 8, 1915.

Application filed January 21, 1914. Serial No. 813,593.

To all whom it may concern:

Be it known that we, HARRY L. MERRIMAN and TONY MAY, citizens of the United States of America, residing at Woodlawn, 5 in the county of Beaver and State of Pennsylvania, have invented certain new and useful Improvements in Rail-Joints, of which the following is a specification, reference being had therein to the accompanying 10 drawings.

This invention relates to rail joints, and has for its object to provide a device of such class, in a manner as hereinafter set forth, for connecting the opposing ends of 15 a pair of track rails together, and at the same time allowing of the contraction and expansion of the track rails.

A further object of the invention is to provide a rail joint, in a manner as herein- 20 after set forth, whereby the track rails are connected together without the employment of threaded bolts and nuts.

Further objects of the invention are to provide a rail joint, which is simple in its 25 construction and arrangement, strong, durable, efficient and convenient in its use, readily set up and knocked down and comparatively inexpensive to manufacture.

With the foregoing and other objects in 30 view, the invention consists of the novel construction, combination and arrangement of parts as hereinafter more specifically described and illustrated in the accompanying drawings, wherein is shown an embodiment 35 of the invention, but it is to be understood that changes, variations and modifications can be resorted to which come within the scope of the claims hereunto appended.

In the drawings wherein like reference 40 characters denote corresponding parts throughout the several views; Figure 1 is a side elevation of a rail joint in accordance with this invention, Fig. 2 is a top plan partly in section, Fig. 3 is a cross sectional 45 view illustrating a locking member in an inoperative position, and Fig. 4 is a cross sectional view illustrating a locking member in an operative position.

Referring to the drawings in detail, 4 50 denotes a plurality of ties for supporting track rails 5 and 6, each of the latter having its web formed with a plurality of openings 8.

Arranged at the sides of the webs 7 are fish plates 9 and 10 each of which is of a 55 length to oppose the webs 8 and each of said fish plates is provided with a plurality of oval-shaped openings 11^a by way of example 4 in number. Each of the fish plates is provided at its lower edge with a base flange 60 11 overlapping one side of the bases 12 of the rails and extended as at 13 to seat upon the ties 4. The extended portions 13 of the base flanges 11 are provided with notches 65 for the passage of the shanks 14 of spikes. The shanks 14 engage in the ties 4 and have heads 15 at their upper ends which overlap the base flanges 11 whereby said flanges are fixedly secured in position. The 70 openings 11^a in the fish plates 9 and 10 75 aline with the openings 8 of the web 7, and extending through each set of alining openings is a locking member 16 having each of its ends provided with a head 17 having the inner face thereof oppositely beveled as at 75 18 and 19, which is adapted to engage the outer face of a fish plate. When the locking member is shifted from the position shown in Fig. 3 to the position shown in Fig. 4, it sets up a wedging action whereby 80 the fish plates 9 and 10 are connected together to the track rails. To prevent the locking member 17 from shifting when in locking position, tie bars 20 and 21 are provided and which extend through the heads 85 17. The tie bars 20 and 21 are oppositely disposed with respect to each other and extending through one end of each of said tie bars is a cotter pin 22. The other end of the tie bar is provided with a handle 23^a. 90 The heads 17 are provided with openings 95 for the passage of the tie bars 20 and 21. The fish plates 9 and 10 extend from the bases 12 to the heads 23 of the rails 5 and 6.

What we claim is:-

In a rail joint, the combination with the abutting rails, of fish plates adapted to wedge into the sides of the rails and to overlap the ends thereof, locking members adapted to extend through elongated holes 100 in the fish plates and the web of the rail between, said locking members having on each end an elongated shaped head with flattened sides, the overhang portion of the head being beveled in each direction on its inner 105 surface, whereby when turned the locking

members engage the fish plates at each end and wedge them against and into the rails, and a tie bar adapted to pass through a plurality of the locking members, whereby 5 to prevent their turning out of locked position, and a key to hold the tie bar locked in place, substantially as and for the purposes described.

In testimony whereof we affix our signatures in the presence of two witnesses.

HARRY L. MERRIMAN.
TONY MAY.
